FUNNEL SUPPORT

Seneca W. Taylor, Iuka, Kans.

Application June 9, 1950, Serial No. 167,028

4 Claims. (Cl. 226—31)

1

This invention relates to funnel-supporting devices for use in filling receptacles, and more particularly to an improved funnel support to be used for supporting a funnel in filling containers through openings in vertical walls of the containers, for example, in filling a horizontal steel drum.

A main object of the invention is to provide an improved funnel support for use in filling receptacles, such as steel drums and the like, said support being very simple in construction, being easy to attach and remove, and enabling an operator to handle a filler can or similar receptacle with both hands without requiring the aid of an assistant to hold the funnel.

A further object of the invention is to provide an improved funnel support adapted for use in filling a horizontal steel drum or the like, said support being very inexpensive to manufacture, being provided with means for securely locking same to the wall of the receptacle to be filled, and being readily detachable from the wall of the receptacle after the filling operation of the receptacle has been completed.

Further objects and advantages of the invention will become apparent from the following description and claims, and from the accompanying drawings, wherein:

Figure 1 is a longitudinal vertical cross-sectional view taken through a steel drum provided in one end wall with an opening in which is positioned an improved funnel support constructed in accordance with the present invention;

Figure 2 is a fragmentary front end elevational view of the drum of Figure 1, showing the improved funnel support in front elevation;

Figure 3 is an enlarged perspective fragmentary detail view of the end of the funnel support which is engageable inside the receptacle.

Referring to the drawings, 11 generally designates a steel drum or similar receptacle having a vertical end wall 12 which is provided in its upper portion with a filler opening 13 which may be closed by the use of a screw plug or the like. Designated at 14 is the improved funnel support, said support comprising a short conduit member which is bent or otherwise formed so that its ends extend at substantial angles to each other, the conduit being shown, by way of example, as being arcuate in shape and having the respective ends 15 and 16. Rigidly secured to the lower portion of the funnel support 14, that is, to its bottom surface, as viewed in Figure 1, and spaced a short distance from the end 16 of the conduit member is a bracket member 17 provided with an

2

outwardly projecting flange 18. The bracket 17 is generally semicircular in shape, as shown in Figure 2, and the flange 18 is coextensive with the semicircular body of the bracket. Rigidly secured to the end 16 at its top surface, as viewed in Figures 1 and 3, is a hook-shaped rod member 19 which faces toward the opposite end 15 of the funnel support member 14.

In using the device, the end 16 is engaged inside the filling opening 13 in the manner shown in Figure 1, the flange 18 abutting the lower outside surface of the filling opening and the hook member 19 engaging over the inner top portion of the filling opening, as clearly shown in Figure 1.

It will be seen from Figure 1 that a funnel, such as the funnel 20 shown in dotted view in Figure 1, may be inserted in the upwardly directed end 15 of the funnel support; and it will be further seen that the funnel 20 will be supported against downward movement by the interlocking engagement of the flange 18 and hook 19 with the respective lower outside and upper inside portions of the opening 13, as shown in Figure 1. The funnel support will be respectively held against lateral rocking, due to the engagement of the end portions of the flange 18 with the side portions of the opening 13, thereby preventing accidental lateral turning of the support conduit 14. The flange 18 provides a substantial bearing having surface engagement with the lower marginal portions of the opening 13, and the hook member 19 provides a sturdy abutment which supports the conduit member 14 against downward rotation.

The funnel support 14 may be readily engaged in the opening 13 by first inserting the hook element 19 and then rotating the conduit member 14 to the position shown in Figure 1, wherein the flange 18 abuts the lower outer marginal portion of the opening 13. The funnel-supporting conduit 14 is removed from the opening 13 by a reverse procedure.

The bracket member 17 may be magnetized so as to be held against the lower outer marginal surface of the opening 13 by magnetic attraction, as well as by the weight of the conduit member 14. By providing such a magnetized bracket member 17, the rigidity of the interlocking engagement of the end 16 of the funnel support with the wall 12 of the receptacle is greatly increased. At the same time, the funnel support may be attached to the wall 12 and may be disengaged from said wall with a minimum amount of manipulation, since it is merely necessary to rotate the conduit member 14 down-

wardly when engaging the end 16 in the opening 13 until flange 18 abuts the lower surface of the opening 13, and to rotate the conduit member in the opposite direction to disengage end 16 from the opening 13.

While a specific embodiment of an improved funnel support for use in filling a container through an opening in a vertical wall thereof has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A funnel support for use with a funnel in filling a container through an opening in a vertical wall of the container comprising a rigid conduit member arranged with its ends extending at a substantial angle to each other, an outwardly extending flat projection on said conduit member adjacent to one end thereof, and another projection on said conduit member diametrically opposite said first-named projection and located substantially closer to said one end than said first-named projection, said last-named projection comprising a hook-shaped element in the form of a U with the bight thereof extending substantially perpendicular to the end of the conduit and the legs thereof extending substantially parallel to the conduit and substantially toward the opposite end of the conduit.

2. A funnel support for use with a funnel in filling a container through an opening in a vertical wall of the container comprising a rigid arcuate conduit member, a flat, outwardly extending flange on said conduit member adjacent to one end thereof, and a projection on said conduit member diametrically opposite said flange and located substantially closer to said one end than said flange, said projection comprising a hook-shaped element in the form of a U with the bight thereof extending substantially perpendicular to the end of the conduit and the legs thereof extending substantially parallel to the conduit and substantially toward the opposite end of the conduit.

3. A funnel support for use with a funnel in filling a container through an opening in a vertical wall of the container comprising a rigid arcuate conduit member arranged with its ends extending at a substantial angle to each other, a magnetized, outwardly extending flat projection on said conduit member adjacent to one end thereof, and another projection on said conduit member diametrically opposite said first-named projection and located substantially closer to said one end than said first-named projection, said last-named projection comprising a hook-shaped element in the form of a U with the bight thereof extending substantially perpendicular to the end of the conduit and the legs thereof extending substantially parallel to the conduit and substantially toward the opposite end of the conduit.

4. A funnel support for use with a funnel in filling a container through an opening in a vertical wall of the container comprising a rigid arcuate conduit member, a flat outwardly extending magnetized arcuate flange on said conduit member adjacent to one end thereof, and a projection on said conduit member diametrically opposite said flange and located substantially closer to said one end than said flange, said projection comprising a hook-shaped element in the form of a U with the bight thereof extending substantially perpendicular to the end of the conduit and the legs thereof extending substantially parallel to the conduit and substantially toward the opposite end of the conduit.
